UNITED STATES PATENT OFFICE

168,730

RADIO-PHONOGRAPH CABINET

Robert D. Budlong, Skokie, Ill., assignor to Zenith
Radio Corporation, a corporation of Illinois

Application October 29, 1952, Serial No. 22,041

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Radio-Phonograph Cabinet, of which the following is a specification, reference being made to the accompanying drawings forming a part thereof.

Figure 1 is a perspective view of the radio-phonograph cabinet, showing my new design;

Figure 2 is another perspective view of the radio-phonograph cabinet showing the cover in the raised position.

The dominant features of my design reside in the portions shown in full lines.

I claim:

The ornamental design for a radio-phonograph cabinet, substantially as shown and described.

ROBERT D. BUDLONG.
